ROTARY EDGER WITH GUARD

Arthur H. Blanchard, 1026 W. Myrtle St.,
Santa Ana, Calif.

Filed Feb. 4, 1959, Ser. No. 791,137

7 Claims. (Cl. 56—25.4)

This invention relates to lawn edgers and more particularly to a rotating guard for electric or internal combustion engine powered edgers.

An object of the invention is to provide a rotating guard for an edger, the guard being mounted for rotation completely independent of the rotation of the cutter of the edger, although the rotation of the cutter and of the guard is about a common axis. The guard serves several purposes, the main purposes being to prevent the cutter from striking cement walks or other things that would be injurious to the cutter when the cutter is in its usual high speed operation; to trap grass for the cutter blade to shear; and to constitute a safety device on the edger.

A guard in accordance with the invention has a toothed wheel which is secured to a flat plate which functions as an axle. A flat retainer is secured to the flat plate, and is held in place by a hub supported on an engine or motor flange, the hub being a ring fitted in the peripheral space between the retainer and toothed wheel. This sub-assembly may be attached directly to the motor or engine, usually an electric motor, behind the rotary cutter, this ordinarily being a single blade which is secured to the motor shaft. Therefore, only the cutter is powered by the motor, and the guard has the guard wheel periphery functioning as a ground contacting member, supporting the weight of the edger, when the user so chooses to use the edger or simply functioning as a safety device, contacting the ground, cement walk or the like before the cutter. Since the guard is made slightly larger in diameter than the length of the cutter blade, the cutter blade is prevented from contacting the walk or the like, this practically always resulting in damage to the cutter or to the motor shaft.

These together with other objects and advantages which will become subsequently apparent reside in the details of construction and operation as more fully hereinafter described and claimed, reference being had to the accompanying drawings forming a part hereof, wherein like numerals refer to like parts throughout, and in which:

Figure 1 is a fragmentary perspective view of an edger furnished with a guard in accordance with the invention.

Figure 2 is a perspective view of the edger in Figure 1 and on a reduced scale.

Figure 3 is an enlarged sectional view taken on the line 3—3 of Figure 1.

Figure 4 is an end elevational view of the edger in Figure 1, portions being broken away and shown in section to illustrate otherwise hidden structure.

In the accompanying drawings there is an edger 10 which shows one configuration of an edger, although the handle 12 may be shaped in different ways. Further, an electric motor 14 is shown attached to the lower end of handle 12, it being clearly understood that the motor and handle are conventional and therefore motor 14

could be substituted by a gasoline powered engine. With the electrical type of edger, which is more common at the present time, electric cable 16 is required, the cable extending through handle 12 that is made hollow for this purpose and to reduce weight.

Collar 18 is secured to the lower end of handle 12 and has a motor mounting flange 20 integral therewith or otherwise secured to it. Bolts 22 may be used for attaching the collar 18 to the lower end of the handle, 10 and in the alternative, other fastening methods may be adopted. The flange 20 is disposed on motor 14 and is attached to it by bolts 22, screws or the like. The motor has a motor shaft 24 projecting from one end of the motor. Blade 26 is, as is usually the case in lawn edgers, made of a flat metal bar with a hub 26' and setscrew 28 carried by the hub and engaging the shaft 24 of motor 14.

Guard 30 is operatively connected with the motor and cutter. Guard 30 is connected with the motor, and for 20 this purpose a flat motor flange 32 is fixed to the motor. Some motors are already equipped with such a flange, and the same holds true for internal combustion engines. Where one is available, it is used in those cases where the guard 30 is to be applied to an existing edger. In 25 original manufacture, though the motor 14 may have the flange 32 integral therewith or otherwise secured to it. Hub 34 is secured to flange 32, and is made of a ring having a central opening 36. The hub is held spaced from flange 32 by means of a plurality of spacers 38, 30 for example washers or short collars, and the mounting bolts 40 are passed through aligned apertures 41 and 42 in hub 34 and flange 32. The bolts also pass through the central opening 43 in the washers or other spacers. When the bolts are tightened, the hub is fixed to the flange 35 32, but is spaced therefrom, leaving an annular recess 46 which is occupied by flat retainer 48.

The flat retainer is a flat circular plate having a central opening 49 through which motor shaft 24 extends. Its 40 peripheral part is mounted for rotation in the annular recess 46, and it has a flat member or plate 52 fixed to it. The flat plate 52 fits flush against the outer face of retainer 48 and is held fixed thereto by means of rivets 54 or the like. The rivets also hold the guard wheel 58 rigidly fixed in assembly with the plate 52 and the flat 45 retainer 48. Guard wheel 58 has a plurality of teeth 60 whose outer edges 62 are flat and which function to engage the ground, a sidewalk or any other object should one be approached and contacted in using the edger. The diameter of the guard wheel 58 is greater than the 50 length of the cutter blade 26 so that the tips of the blade will not contact the sidewalk, driveway, or other concrete or hard object. Rather, the guard wheel will engage such objects, holding the tips of the blades spaced therefrom.

55 As shown in Figure 3 retainer 48 has a diameter greater than the diameter of plate 52, and the guard wheel 58 also has a diameter which is greater than the diameter of the plate 52. This forms an annular recess 70 between opposing surfaces of the retainer 48 and the guard wheel 58, occupied by hub 34.

From the foregoing and Figure 3 it is evident that the 60 shaft 24 is passed through aperture 49 and aligned apertures 78, 79 and 80 in retainer 48, plate 52 and guard wheel 58 respectively. The cutter blade is rotated by rotation of shaft 24, but the guard 30 is independently rotatable with its plate 52 and retainer 48.

The foregoing is considered as illustrative only of the 65 principles of the invention. Further, since numerous modifications and changes will readily occur to those skilled in the art, it is not desired to limit the invention to the exact construction and operation shown and de-

scribed, and accordingly all suitable modifications and equivalents may be resorted to, falling within the scope of the invention as claimed.

What is claimed as new is as follows:

1. In a lawn edger which has a shaft, a power producing device with which said shaft is connected, a mounting flange fixed to said power producing device and having an aperture through which said shaft extends, a cutter attached to said shaft and rotatable by the shaft, a guard located between said device and said cutter and including a guard wheel having a diameter greater than the length of said cutter, a hub attached to said flange, a flat plate attached to said guard wheel, and means connected with said flat plate and engaged between said hub and flange mounting said guard wheel for rotation independent of the rotation of said cutter.

2. In a lawn edger which has a shaft, a power producing device with which said shaft is connected, a mounting flange fixed to said power producing device and having an aperture through which said shaft extends, a cutter attached to said shaft and rotatable by the shaft, a guard located between said device and said cutter and including a guard wheel having a diameter greater than the length of said cutter, a hub attached to said flange, a flat plate attached to said guard wheel, means connected with said plate and engaged between said hub and flange mounting said guard wheel for rotation independent of the rotation of said cutter, said means including a flat retainer attached to said plate, spacers connected between said hub and said flange thereby holding said hub spaced from said flange and providing an annular recess therebetween, and said retainer having a peripheral portion which occupies said recess.

3. In a lawn edger which has a shaft, a power producing device with which said shaft is connected, a mounting flange fixed to said power producing device and having an aperture through which said shaft extends, a cutter attached to said shaft and rotatable by the shaft, a guard located between said device and said cutter and including a guard wheel having a diameter greater than the length of said cutter, a hub attached to said flange, a flat plate attached to said guard wheel, means connected with said plate and engaged between said hub and flange mounting said guard wheel for rotation independent of the rotation of said cutter, said means including a flat retainer attached to said flat plate, spacers connected between said hub and said flange thereby holding said hub spaced from said flange and providing an annular recess therebetween, said retainer having a peripheral portion which occupies said recess, said flat retainer having a diameter greater than the diameter of said flat plate, said guard wheel having a diameter greater than the diameter of said flat plate thereby providing an an-

nular recess between said retainer and said guard wheel, and a portion of said hub occupying the last mentioned recess.

4. In a lawn edger which has a shaft, a power producing device with which said shaft is connected, a mounting flange fixed to said power producing device and having an aperture through which said shaft extends, a cutter attached to said shaft and rotatable by the shaft, a guard located between said device and said cutter and including a guard wheel having a diameter greater than the length of said cutter, a hub attached to said flange, a flat plate attached to said guard wheel, means connected with said plate and engaged between said hub and flange mounting said guard wheel for rotation independent of the rotation of said cutter, said means including a flat retainer attached to said plate, spacers connected between said hub and said flange thereby holding said hub spaced from said flange and providing an annular recess therebetween, said retainer having a peripheral portion which occupies said recess, said retainer and plate and guard wheel each being superposed, fasteners attached to said retainer and said guard wheel holding said retainer and said flat plate and said guard wheel assembled as a unit, and said retainer and said flat plate and said guard wheel having aligned apertures through which said shaft extends.

5. A guard for a lawn edger which has a power producing device having a shaft, said guard including a guard wheel, a flat plate attached to said guard wheel, a flat retainer attached to said plate, said guard wheel and said plate and said retainer each being parallel, and fasteners securing said guard wheel, said plate and said retainer together to form a unit.

6. The combination of claim 5 wherein said guard wheel has a plurality of approximately radial teeth to temporarily hold grass, weeds and the like, and a cutter attached to said shaft and operable in a plane parallel to the plane of said flat guard wheel to sever the held grass and disposed outwardly of said guard wheel.

7. The combination of claim 5 wherein said guard wheel has a plurality of approximately radial teeth to temporarily hold grass, weeds and the like, a cutter attached to said shaft and operable in a plane parallel to the plane of said flat guard wheel to sever the held grass, and said cutter being a flat plate with a length smaller than the diameter of said guard wheel.
